CLAIM

The ornamental design for an enclosure for a switch having sloping and convex curved top, as shown and described.

DESCRIPTION

FIG. 1 is a front perspective view of an enclosure for a switch having sloping and convex curved top according to the present disclosure;

FIG. 2 is a front view of the enclosure for a switch having sloping and convex curved top of FIG. 1;

FIG. 3 is a rear view of the enclosure for a switch having sloping and convex curved top of FIG. 1;

FIG. 4 is a first side view of the enclosure for a switch having sloping and convex curved top of FIG. 1;

FIG. 5 is a second, opposite side view of the enclosure for a switch having sloping and convex curved top of FIG. 1;

FIG. 6 is a top view of the enclosure for a switch having sloping and convex curved top of FIGS. 1; and,

FIG. 7 is a bottom view of the enclosure for a switch having sloping and convex curved top of FIG. 1.

The broken line portions in the figures are included to show portions of the enclosure that form no part of the claimed design.
